UNITED STATES PATENT OFFICE.

EMIL C. RAUSCHENBERG, OF WHEELING, WEST VIRGINIA, ASSIGNOR TO WHEELING MOLD & FOUNDRY CO., OF WHEELING, WEST VIRGINIA.

CAST-METAL ANNEALING BOX.

Application filed December 28, 1922. Serial No. 609,415.

To all whom it may concern:

Be it known that I, EMIL C. RAUSCHENBERG, a citizen of the United States, residing at Wheeling, in the county of Ohio and 5 State of West Virginia, have invented certain new and useful Improvements in Cast-Metal Annealing Boxes, of which the following is a specification, reference being had therein to the accompanying drawing.

10 This invention relates to improvements in cast metal annealing boxes and it pertains to the particular construction of the cast box whereby it will stand up under external heat and expand and contract without cracking.

15 The annealing box here shown is for the purpose of enclosing piles of sheet plate to be annealed. The sheet plate is piled upon a cast iron truck, the annealing box placed over the piled sheets and then sand or clay 20 is laid around the bottom of the box making a tight seal, or the cast iron truck may have sand placed on it, the plates then piled on the truck, and the box placed over the piled sheets the lower edge of the box embedding 25 itself in the sand or clay. From the foregoing it will be understood that an annealing box is subjected to heat from the outside, the heat being conveyed to the plates to be annealed. It therefore follows that in con- 30 structing a box to withstand the action of the heat that it must be properly braced so as to prevent it from falling, and at the same time capable of expansion and contraction.

35 One object of my present invention is to provide an annealing box having long corrugations which are separated by a straight wall, whereby the straight portion between the corrugations brace the wall of the box and prevent it from falling in under the 40 action of the external heat, the straight portion acting as a stiffening member between the corrugations.

45 A further object of my present invention is to make the corrugations deeper at the center of the top of the box whereby additional stiffness is added to the top of the box which prevents it from falling in under the action of external heat.

50 A further object of my present invention is to provide a box having a vertical corrugation in each end which begins at near the bottom of the box and extends upward merging in the top of the box, whereby the ends are stiffened by the corrugation, and the

straight portion at each side of the corrugation, and will be prevented from falling in. 55

A further object of my present invention is to provide a cast box having its corners rounded, whereby the rounded portions will act as a stiffening for the box, together with the intermediate vertical corrugation in the ends of the box, and with the corrugation in the sides and top of the box, there remaining a stiffening straight portion between the last 60 said corrugation and the corners of the box. 65

Other objects of the invention will herein-after appear from the description and disclosure.

Referring to the drawings, Fig. 1 is a combined plan view and central horizontal 70 sectional view of a box embodying my present improvement.

Fig. 2 is a combined side elevation and vertical central sectional view of my improved box. 75

Fig. 3 is an end elevation of the improved box.

Fig. 4 is a transverse vertical sectional view taken on a line between two of the corrugations. 80

Fig. 5 is a vertical sectional view taken through the center of one of the corrugations.

My improved box is composed of cast metal and as shown the thickness of the 85 metal is uniform throughout with the exception of a rib at the bottom. One improvement of my present invention is in providing the box with a plurality of long corrugations 1 which are separated by 90 straight intermediate portions 2. These corrugations 1 begin at an internal rib 3 at the bottom of the box and extend upward and over the top as shown. Attention is directed to the fact that the corrugation where 95 it extends across the top of the box is made gradually deeper so that at the center point 4 of the top it is considerably deeper than at any other point. This will provide the center of the top of the corrugation with 100 additional stiffness to prevent the top itself from caving in from its own weight, thus providing a stiffening for the box in places where it is highly needed.

The rib 3 extends around the inner side of 105 the box where it is not subjected to external heat and it provides improvements for sustaining the weight of the whole box prevent-

ing it from falling down as it might do under the external heat since the weight of the whole box is upon its lower edge.

The ends of the box are provided with 5 vertical ribs 6 that begin at the point 7 near its lower edge and extend upward throughout the heights of the box gradually merging into the straight portions 5 of the top of the box as shown at 8. For the purpose of strengthening the corners of the box 10 I make them rounded as at 9 so that the rounded portions form stiffening elements which are located between the corrugations of the top of the box and the corrugation 6 15 in the end of the box.

The body of the box is provided with cast 15 projections 9' adapted to receive an instrument for handling the box.

By means of the described construction I 20 produce a cast metal box with the corrugations which provide for the expansion of the box the said corrugations being separated by straight stiffening portions 2 combined with the stiffening corrugations for the ends of 25 the box.

In practice the box constructed as above described is found to stand many more heatings without falling or cracking than boxes which are made of continuous corrugations 30 that have a tendency to expand so much and fall in their expansion; and I find that a box constructed as above described will stand many more heatings than any other annealing box known to me.

35 What I claim and desire to protect by Letters Patent is:

1. A cast metal annealing box having its

body portion provided with depressed corrugations extending upward and continuous across the center of its top, said depressions 40 being separated by straight stiffening portions.

2. A cast metal annealing box the body of which is provided with vertical corrugations extending upward and across the top 45 of the box, the corrugations being deepest at the center of the top of the box, for the purpose described.

3. A cast metal annealing box having an open lower end provided with an internal 50 rib around its lower edge, the sides and top of the box having transverse depressed corrugations beginning at the said rib and extending continuously across the top of the box, the said corrugations being separated 55 by straight stiffening portions.

4. A cast metal box the body of which is provided with vertically extending depressed corrugations which extend continuously 60 across the box, the corrugations separated by straight stiffening portions and the end corrugations removed from the corners of the box, for the purpose described.

5. A cast metal annealing box the body of which is provided with vertical corrugations 65 extending across the top of the box, the ends of the box having intermediate corrugations, the tops of the intermediate corrugations merging into the top of the box, the parts combined and operating for the purposes 70 described.

In testimony whereof I hereunto affix my signature.

EMIL C. RAUSCHENBERG.
